UNITED STATES PATENT OFFICE.

DEWITT C. CREGIER, OF CHICAGO, ILLINOIS.

STREET-RAILWAY RAIL.

SPECIFICATION forming part of Letters Patent No. 369,398, dated September 6, 1887.

Application filed December 21, 1886. Serial No. 222,143. (No model.)

To all whom it may concern:

Be it known that I, DEWITT C. CREGIER, a citizen of the United States, residing in Chicago, county of Cook, and State of Illinois, 5 have invented certain new and useful Improvements in Street-Railway Rails, of which the following is a specification.

This invention relates to street-railway rails in which there are two contiguous tramways, 10 one for the car-wheels and the other for wheels of ordinary vehicles, which rails have at regular and uniform intervals spike-holes at the center of width of the tramway for ordinary vehicles, and are secured to stringers conforming to the angle of the rails by headed spikes driven through said holes into the stringers.

In the form of rails above referred to the spike-heads are exposed to the action and wear of vehicle-wheels passing over them, and are 20 frequently destroyed or partially destroyed to such an extent as to render them no longer useful and to prevent their removal from the stringer at all without enlarging the spike-recess in the stringer to such a degree that only 25 a larger-sized spike that could not pass through the perforation in the rail can be tightened in such enlarged recess. As a result of all this, the rail must be entirely removed, cut, and then shifted, so that none of its series of spike-holes will register with the recesses of the removed spikes or with the spikes, from which 30 the heads have been broken or driven flush with the face of the stringer, and after such shifting a piece of rail must then be inserted to supply the place of the piece cut from the rail, and this necessitates frequent and expensive repairs and a serious interruption of traffic on the street. A more serious objection, 35 however, to this commonly-used rail is the enlargement of the spike-holes therein by a friction between the spike and rail, caused by a lateral strain and movement of the rail upon the spike from the lateral strain against the car-wheel tramway by heavy vehicles when 40 turning in or out from the track, which lateral strain not only produces such an enlargement of the holes that the spike-head loses its gripping-force, but frequently loosens the spike in the stringer, because of the leverage of the 45 rail on the spike, owing to the location of the spike between the center of width and inner edge of the rail; and rails having their per-

forations so worn are commonly condemned and their place supplied with new rails rather than spend the time and incur the expense of 55 supplying and fitting varying sizes of spikes necessary to further utilize the rails.

The objects of my invention are therefore to avoid these objectionable features which result in the commonly-used rail, and to increase the strength and wear of the rail, and also to isolate the spike-head from contact with vehicle-wheels, and at the same time reduce the leverage of the rail on the spike to a minimum, without any substantial change in the 65 form of outline or a contraction in the working-surface of my rail from the rail now commonly used. These objects are attained by a form of construction of street-car rail illustrated in the accompanying drawings, in which—

Figure 1 represents a transverse section of a rail embodying my invention secured in its operative position to a stringer conforming on its upper surface to the configuration of the rail; Fig. 2, a top plan view of the same; Fig. 75 3, a key-bolt, which may be used in securing the rail to the stringer.

Similar letters of reference indicate the same parts in the several figures of the drawings.

A designates a street-car rail mounted upon 80 a stringer, B, and having two tramways, one tramway, C, of which is for the car-wheel and the other tramway, D, for the wheels of ordinary vehicles, said tramways being contiguous and so joined by a web, H, and provided with a 85 channel or groove, E, extending longitudinally of the rail and therefore parallel with the tramways. The side walls of the channel are formed by the opposing walls of the tramways, and the bottom of the channel by the web H, in 90 which at regular intervals are a series of holes through which spikes are passed and then driven to secure the rail thereto.

As shown, the channel E is of greater depth than the head of the spike G, securing the rail 95 to the stringer; but it would be no departure from my invention to have an equal depth of channel and spike-head, so long as the spike-head does not project above the plane of the surface of the tramway D, so that it may have 100 contact with the wheels of vehicles passing over it to a degree sufficient to disturb or wear the spike-head. In practice, however, it is preferred to have the channel of a depth in-

suring the depression of the spike-head below the tramway D, as shown, so that a slight increase in depth of a standard depth of spike-head will insure any such spike-heads projecting above the face of the vehicle-tramway and the depression of the spike-head from contact with the flange of the car-wheel as the tramway C becomes worn down.

When it is desirable to have the channel E of a minimum width and of such a width that the narrowest vehicle-wheels cannot catch or wedge in the channel, the T-spike G—that is to say, a spike the head of which has considerable length on both sides of the spike, but a width corresponding substantially to the diameter of the spike—is employed; but it would be no departure from my invention to increase the width of the channel to such a width that vehicle-wheels may pass into it, and to use in connection therewith spikes having broad heads and of the ordinary construction, for in such case the channel, after the spikes are driven, may be filled with a concrete cement, iron or steel borings or turnings, asphalt cement, or any other material suitable for such purposes; but such filling, as before stated, may be omitted when the width of the channel is of such a degree as to not make it necessary; nor is my invention limited to the employment of any special kind of fastening device for securing the rail to the stringer, for instead of the ordinary or special form of spike before referred to, which may or may not be split, as indicated by dotted lines at *a*, Fig. 1, a bolt, J, (shown in Fig. 3,) and provided with a key or other suitable locking and tightening device, may be employed, as also shown in dotted lines at *b*, Fig. 1.

The channel E is preferably formed in the rail at substantially the center of width thereof, for the purpose of relieving, as it does, the spike from any leverage on the part of the rail, and the web H is of a thickness to render the rail strong and durable; but in considering my invention, broadly, as a novel

means of isolating a spike-head from contact with vehicle-wheels, and as a means for avoiding the objections necessarily following such a contact, my invention is not limited to the location of the channel at the point shown 50 with reference to the width of a rail of this general character, for the channel may be at any other point, so long as it does not obstruct the free passage of car-wheels and the wheels of other vehicles along the tramway, or materially diminish the strength and durability of the rail.

Rails such as I have described need not necessarily be mounted upon or secured directly or otherwise to wood stringers, but may be 50 used in connection with metal supports forming stringers, or to chairs secured to cross-ties, as shown and described in another application filed herewith, and the channels in such rails may be simultaneously formed in rolling the 65 rail or by channeling the rail after it is otherwise completed.

Having described my invention, what I claim, and desire to secure by Letters Patent, is—

1. A street-car rail having two trams in differing planes, and a channel parallel with and between said trams, said channel being provided with spike or bolt holes, substantially as described.

2. A street-car rail having double trams in differing planes and of corresponding face-diameters, and provided with a longitudinal channel between said trams, said channel having spike or bolt holes therein, substantially as described, whereby the spike or bolt head is isolated from contact with both vehicle and car wheels, and the leverage of such a rail on its support and on the spike or bolt is reduced to a minimum.

DEWITT C. CREGIER.
